DESIGN FOR A FERRULE FOR USE ON UTENSILS OR SIMILAR ARTICLES

Simon W. Farber, Brooklyn, N. Y.

Application December 30, 1939, Serial No. 89,234

Term of patent 14 years

To all whom it may concern:

Be it known that I, Simon W. Farber, a citizen of the United States, residing at Brooklyn, in the county of Kings and State of New York, have invented a new, original, and ornamental Design for a Ferrule for Use on Utensils or Similar Articles, of which the following is a specification, reference being had to the accompanying drawing, forming part thereof, wherein—

Fig. 1 is a perspective view of a ferrule showing my new design; and

Fig. 2 is a horizontal sectional view taken through the center thereof.

I claim:

The ornamental design for a ferrule for use on utensils or similar articles, substantially as shown.

SIMON W. FARBER.
